PHONOGRAPH RECORD CHANGER BASE

Earl E. Hoyt, Northvale, N.J., assignor to BSR (USA) Limited, Blauvelt, N.Y.

Original design application Dec. 2, 1968, Ser. No. 14,732, now Patent No. 217,295, dated Apr. 21, 1970. Divided and this application Sept. 9, 1969, Ser. No. 19,077

Term of patent 14 years

Int. Cl. D14—01

U.S. Cl. D56—4

FIG. 1 is a perspective view of a phonograph record changer base embodying the new design, showing also record changer structure in broken lines.

FIG. 2 is a plan view of the record changer base of FIG. 1.

FIG. 3 is a vertical section on line 3—3 of FIG. 2.

FIG. 4 is a vertical section on line 4—4 of FIG. 2.

The broken line showing of a representative record changer mechanism in FIG. 1 is for illustrative purposes only.

I claim:

The ornamental design for phonograph record changer base, as shown and described.
